US00D917131S

(12) **United States Design Patent** (10) **Patent No.:** **US D917,131 S**
(45) **Date of Patent:** **** Apr. 27, 2021**

(54) **INFANT BIB**

(71) Applicant: **i play. inc.**, Asheville, NC (US)
(72) Inventors: **Becky B. Cannon**, Asheville, NC (US);
Emi Kubota, Asheville, NC (US)
(73) Assignee: **Green Sprouts, Inc.**, Asheville, NC (US)
(**) Term: **15 Years**
(21) Appl. No.: **29/660,939**
(22) Filed: **Aug. 23, 2018**
(51) LOC (13) Cl. **02-02**
(52) U.S. Cl. **USPC D2/864**
(58) **Field of Classification Search**
USPC D2/864, 861, 863
CPC A41B 13/10; A41B 13/103; A41B 13/106
See application file for complete search history.

(57) **CLAIM**

The ornamental design for an infant bib, as shown and described.

DESCRIPTION

FIG. 1 is a frontal perspective view of an infant bib of our new design.

FIG. 2 is a front elevation view of the infant bib of our new design.

FIG. 3 is a rear elevation view of the infant bib of our new design.

FIG. 4 is a right side view of the infant bib of our new design.

FIG. 5 is a left side of the infant bib of our new design.

FIG. 6 is a top plan view of the infant bib of our new design.

FIG. 7 is a bottom plan view of the infant bib of our new design; and,

FIG. 8 is a frontal perspective view of the infant bib of our new design folded for storage.

The broken lines in the drawings are included for the purpose of illustrating unclaimed features and form no part of the claimed design.

1 Claim, 5 Drawing Sheets
